[57] CLAIM

The ornamental design for a combination cigarette lighter bracket and extended tip, as shown.

DESCRIPTION

FIG. 1 is a side elevational view of the present combination cigarette lighter bracket and extended tip showing my new design;

FIG. 2 is a top plan view of FIG. 1;

FIG. 3 is a bottom plan view of FIG. 1;

FIG. 4 is an end elevation taken from the left hand end of FIG. 1; and

FIG. 5 is an end elevational view taken from the right hand end of FIG. 1.
